UNITED STATES PATENT OFFICE.

WILLIE H. SALYERS, OF TUCUMCARI, NEW MEXICO.

VEHICLE, IMPLEMENT, AND WAGON-TONGUE ATTACHMENT.

1,059,219.

Specification of Letters Patent. Patented Apr. 15, 1913.

Application filed September 24, 1912. Serial No. 722,097.

To all whom it may concern:

Be it known that I, WILLIE H. SALYERS, a citizen of the United States, residing at Tucumcari, in the county of Quay and State 5 of New Mexico, have invented new and useful Improvements in Vehicle, Implement, and Wagon-Tongue Attachments, of which the following is a specification.

This invention has relation to a tip for 10 wagon poles or tongues, the object being to provide an adjustable stop for the neck yoke, whereby the same may be readily adjusted for long or short coupled horses.

The invention consists of a metal tip provided with a guide, a stop adjustable in the 15 guide, and means for securing the stop in the adjusted position, said means being easily operable and arranged to be protected from injury.

20 The invention consists of the novel features, details of construction and combination of parts, which hereinafter will be more particularly set forth, illustrated in the accompanying drawing, and pointed out 25 in the appended claim.

Referring to the drawing, forming a part 30 of the specification, Figure 1 is a side view of the forward end of a vehicle pole provided with a metal tip and adjustable stop embodying the invention. Fig. 2 is a longitudinal section of the parts illustrated in 35 Fig. 1. Fig. 3 is a transverse section on the line $x-x$ of Fig. 1. Fig. 4 is a detail perspective view of the adjustable stop and means whereby the same is secured to the tip in the adjusted position.

40 Corresponding and like parts are referred to in the following description, and indicated in all the views of the drawings, by the same reference characters.

The metal tip 1 is in the nature of a sleeve or socket to be slipped upon the end of the pole or tongue 2, said tip having an extended bottom side to fit long poles so as to provide 45 for ample adjustment of the neck yoke stop. A guide 3 is provided upon the bottom side of the tip 1 and consists of inturned or re-curved flanges. A plurality of openings 4 are formed in the bottom side of the tip between the side flanges or members of the 50 guide 3. The tip when slipped upon the end of the pole or tongue 2 may be secured in any manner, as by rivets 5.

The neck yoke stop comprises a base 6 and a stud 7, the latter being pendent from 55 the forward end of the base 6 and having a depression 8 near its upper end upon the forward side to provide a seat to receive the eye 9 of the neck yoke 10. A brace 11 is secured to the lower end of the stud 7 and 60 to the rear end of the base 6. A spring 12 is secured at one end to the stud 7 and its opposite end passes through an opening 13 of the base 6 and projects above said base to enter any one of the openings 4 so as to 65 hold the neck yoke stop in the adjusted position along the pole tip. The brace 11 besides strengthening the stud 7 also forms a guard to protect the spring 12.

After the tip has been slipped upon the 70 end of the pole or tongue 2 and made fast the neck yoke stop is fitted in the guide 3 and moved to the adjusted position, being held fast by means of a pin or thickened part at the free end of the spring 12, which 75 enters the selected opening of the series 4. When it is required to adjust the neck stop the rear end of the spring 12 is depressed, thereby withdrawing its end or the pin carried thereby from engagement with the tip 80 when the stop may be moved in the guide 3 to the required position and upon releasing the spring 12 the stop will be held fast in the manner stated.

From the foregoing description, taken in 85 connection with the accompanying drawing, the advantages of the construction and of the method of operation will be readily apparent to those skilled in the art to which the invention appertains, and while I have 90 described the principle of operation of the invention, together with the device which I now consider to be the best embodiment thereof, I desire to have it understood that the device shown is merely illustrative, and 95 that such changes may be made when desired as are within the scope of the claim appended hereto.

Having thus described the invention what is claimed as new, is:—

100 In combination a pole tip provided with a guide, and a plurality of openings along the length of the guide, a neck yoke stop comprising a base and a pendent stud slidably mounted in the guide, a brace connecting the lower end of the stud with the rear

portion of the base, and a spring secured at one end to the stud and having its opposite end portion extending through an opening in the base and adapted to engage any one of the openings of the tip to hold the stop in the adjusted position, said spring being arranged between the base and brace.

In testimony whereof I affix my signature in presence of two witnesses.

WILLIE H. SALYERS.
